UNITED STATES PATENT OFFICE.

CHARLES GILBERT DAVIS, OF FREEMAN, CANADA.

WIRE-SPlicer.

SPECIFICATION forming part of Letters Patent No. 632,446, dated September 5, 1899.

Application filed January 20, 1899. Serial No. 702,829. (No model.)

To all whom it may concern:

Be it known that I, CHARLES GILBERT DAVIS, manufacturer, of the village of Freeman, in the county of Halton, in the Province of 5 Ontario, Canada, have invented certain new and useful Improvements in Wire-Splacers, of which the following is a specification.

My invention relates to improvements in wire-splacers; and the object of the invention 10 is to design a splicer whereby the ends of the wires used, particularly in fences, may be securely and easily fastened together; and it consists, essentially, of two bent arms, preferably broadly V-shaped in form and having 15 one overlapping the other and pivoted to it, the end of one arm being peculiarly formed and provided with a serpentine groove and a central passage-way, the parts being otherwise constructed and arranged in detail, as 20 hereinafter more particularly explained.

Figure 1 is a perspective view of my device, showing it in position for actual operation. Fig. 2 is a similar view showing the ends of 25 the arms sprung apart so as to permit of the wire which forms the core for the binding-wire being inserted. Fig. 3 is a cross-section.

In the drawings like letters of reference indicate corresponding parts in each figure.

A is one bent arm and B the other, which 30 are suitably pivoted on the central bolt b. The upper end a of the arm A has a certain amount of spring in it and is provided with a depression a', forming a teat at the opposite side, which is designed to fit into a hole b' in order 35 to hold the arms together when they are in operative position, as shown in Fig. 1.

The arm B is formed substantially cylindrical with a central passage-way b² and a serpentine groove b³, which extends from end to 40 end of the portion B', as shown. A notch b⁴ is provided at the outer end. The core-wire is in a central position, as indicated in Fig. 2. Of course when the two wires are joined together, as indicated in Fig. 1, one of the wires 45 in each case forms the core to twist the other upon.

When the wire has been inserted, as shown

in Fig. 2, the lower portion of the arm A is thrown down, so as to throw the lug a² of the arm A over the top of the core-wire, thereby 50 securely maintaining it in the passage-way b². The other end of the wire is forced into the center of the passage-way, as indicated by dotted lines in Fig. 2. The wire which it is desired to twist upon the core-wire is then 55 inserted into the notch b⁴, being first brought up into the position shown in dotted lines in Fig. 1, and thus the twist is given, as indicated in this figure, by simply twisting around the arms on the core-wire. 60

Such a device as I describe is simple and easy to operate, and the splices, as shown, may be readily and quickly made.

What I claim as my invention is—

1. A splicer for wire comprising two bent 65 arms suitably pivoted together, the end of one being provided with a central passage-way, a serpentine groove extending from end to end of the same, and a notch at the outer end, as and for the purpose specified. 70

2. A splicer for wire comprising two bent arms suitably pivoted together, the end of one being provided with a central passage-way, a serpentine groove extending from end to end of the same, and a notch at the outer end, and 75 the other arm being provided with a lug a² designed to overhang the inner end of the serpentine groove and passage-way, as and for the purpose specified.

3. The combination with one bent arm provided with a central passage-way, a serpentine groove extending from end to end and a notch at the outer end, of the coacting arm suitably pivoted on the aforesaid arm and having a spring end provided with a teat formed at its 80 opposite end designed to engage when the arm is closed with a hole on the corresponding end of the aforesaid arm, as and for the purpose specified. 85

CHARLES GILBERT DAVIS.
